(57) **CLAIM**

We claim, the ornamental design for a pendant light, as shown and described.

DESCRIPTION

FIG. 1 is a perspective view of a pendant light depicting our design;

FIG. 2 is a side elevation view thereof, wherein the pendant light is rotationally symmetrical about its main axis;

FIG. 3 is a top plan view thereof;

FIG. 4 is a bottom plan view thereof; and,

FIG. 5 is a perspective view thereof; shown with unclaimed subject matter removed for clarity of illustration.

The phantom lines shown in FIG. 1—FIG. 5 are environmental and not part of the claimed design.

References to “side”, “top”, “front” and “rear” in the figure descriptions are not meant to require certain in-use orientation, a pendant light according to the claimed design may be used in any orientation.
